(57) **CLAIM**

The ornamental design for a travel container for powdered substances, as shown and described.

DESCRIPTION

FIG. 1 is a perspective view of the travel container for powdered substances showing my new design, with the tip and bottom lids shown closed;

FIG. 2 is right side perspective view thereof, with the tip and bottom lids shown open;

FIG. 3 is a left side perspective view thereof, with the tip and bottom lids shown open;

FIG. 4 is a right side view thereof;

FIG. 5 is a left side view thereof;

FIG. 6 is a rear view thereof;

FIG. 7 is a front view thereof;

FIG. 8 is a top view thereof; and,

FIG. 9 is a bottom view.

The broken line showing of environment in the drawings is included for the purpose of illustrating only and forms no part of the claimed design.
